UNITED STATES PATENT OFFICE.

GEORGE SABIK, OF CHICAGO, ILLINOIS, ASSIGNOR TO U. S. DUPLICATOR COMPANY, OF CHICAGO, ILLINOIS, A CORPORATION OF ILLINOIS.

DUPLICATING MACHINE.

Application filed April 9, 1920. Serial No. 372,455.

To all whom it may concern:

Be it known that I, GEORGE SABIK, a citizen of the United States, residing at Chicago, in the county of Cook and State 5 of Illinois, have invented certain new and useful Improvements in Duplicating Machines, of which the following is a specification.

This invention relates to a duplicating or 10 copying machine by which a number of copies of a written or typewritten sheet can be made through the agency of an impression sheet on which the original writing is recorded and from which the copies are 15 made.

The principal object of the invention is to provide an improved machine having improved means for winding and moving the impression sheet. Another object is to provide 20 an improved frame for supporting a sheet and the mechanism by which the sheet is operated. Still another object is to provide improved means for mounting the rollers on which the impression sheet is wound. 25 Other objects relate to various features of construction and arrangement which will appear more fully hereinafter.

The nature of the invention will be understood from the following specification taken 30 with the accompanying drawings in which one embodiment is illustrated.

In the drawings—

Fig. 1 shows a top plan view of the invention;

Fig. 2 shows a side elevation thereof;

Fig. 3 shows a perspective view of one end of one of the rollers;

Fig. 4 shows a longitudinal section through the machine on the line 4—4 of 40 Fig. 1;

Fig. 5 shows a sectional view on the line 5—5 of Fig. 6;

Fig. 6 shows a transverse sectional view on the lines 6—6 of Fig. 2; and

Fig. 7 shows a vertical section on the line 7—7 of Fig. 6.

The frame of the machine is formed of sheet metal which is rolled and bent to form an integral frame construction comprising side frame members 10 formed integrally with an upper horizontal bed or table 11. The side frame members 10 have legs 12 formed integrally therewith and these legs have their ends bent transversely to 55 form flanges 13 adapted to rest on a suitable

support. The legs 12 of the machine are united by transverse rods 14. The side frame members are further united at their upper ends by means of transverse bars 15 which are formed integrally with the side frame members. In forming the frame the sheet metal is cut away at the ends of the table 11 to form the slots or apertures 16 and 17 between the table and the bars 15.

The impression sheet 20, formed of a gelatinous composition or other suitable material adapted to form an impression of the writing to be reproduced, is adapted to be supported upon the table 11 and the ends of this sheet pass through the slots 16 and 17 and are wound upon the rolls 21 and 22.

The unused roll of the sheet 20 is wound on the roller 21 and as the successive portions of this sheet are used for copying purposes, the sheet is wound up on the other roll 22 and unwound from the roller 21. The ends of the table 11 are curved downwardly at their extremities 11^a in order to permit the impression sheet to pass thereover without danger of injury. The sheet 20 is guided and maintained in contact with the table at the feeding end by means of a movable guide member 24 which is carried by arms 25 pivoted at 26 on the side frame members 10. This bar 24 of angle cross-section rests on the sheet 20 above the slot 16 and it is provided at its ends with blocks 27 secured in the angle thereof to receive between them the sheets of paper to be copied and those on which copies are to be made.

Each of the rollers 21 and 22 is provided at one end with a trunnion 30 having an enlarged portion 30^a secured in the end of the roller and a smaller portion 30^b adapted to engage a slot 31 in one of the side frame members 10. Each of these slots terminates at one end at the point where the trunnion 30 is normally adapted to rotate and it extends longitudinally therefrom toward the end of the frame, as shown in Fig. 5. The slot is enlarged toward its outer end in order to receive the trunnion readily and after the trunnion has been passed into engagement with the slot, it is maintained in its normal position engaging the small end of the slot by means of a latch member 33 which is pivoted on the side frame member at 34 and provided with a downward extension 33^a having a notch or recess 33^b formed therein to engage the reduced por-

- tion 30^b of the trunnion. The downward extension 33^a has an inclined surface 35 with which the trunnion is adapted to coact when it is being passed to its normal position.
- 5 The latch member 33 is normally forced in a downward direction by means of a wire spring 36 which is secured to the side wall of the frame by clamping tongues 37 which are punched out of the sheet metal of the frame. The part 33^a of the latch member is offset inwardly upon the side frame and is adapted to coact with the shoulder on the trunnion at the end of the enlarged part 30^a, as shown in Fig. 6. The end of the handle 10 portion of the latch member is bent around the side frame in order to prevent inward displacement thereof. The downward movement of each latch is limited by an inwardly turned lug 38 formed on the upper edge of 15 the slot.
- 15 The other ends of the rollers 21 and 22 are supported by the winding shafts 41 and 42 which are journalled within the bearing members 43 and 44 secured to the outer side 20 of one of the side frame members 10 by means of screws 45. These shafts 41 and 42 have handles 47 and 48, respectively, secured to the outer ends thereof by means of the screws 49 and the bearings 43 and 44. 25
- 30 are provided at their inner ends with recesses adapted to receive the ratchet wheels 51 and 52, respectively. These ratchet wheels are secured to the shafts and the rotation thereof is controlled by the detents 35 53 and 54 which are pivoted on the pins 55 within slots 56 formed in the upper sides of the bearing members. These detents have handles 57 adapted to be manually engaged by the operator and they normally rest by 40 gravity on the teeth of the ratchet wheels.
- Each of the shafts 41 and 42 carries at its inner end a block 60 of rectangular cross section which is provided with a slot 61 in axial alinement with the connected shaft.
- 45 Each block 60 and the slot 61 therein is adapted to be engaged by a bracket member 62 secured to the end of the adjacent roller 21 or 22. Each bracket 62 is somewhat Z-shaped in cross section and is provided with a central web 62^a and oppositely directed end flanges 62^b and 62^c. When the web 62^a of the bracket passes into engagement with the slot 61, the flanges 62^b and 62^c are adapted to overlie and contact with the opposite parallel surfaces of the block 60 at the end of the slot 61. The bracket 62 is located with its center on the longitudinal axis of the connected roller and the block 60 has its axis coincident with the 55 axis of the connected shaft, so that this arrangement serves to hold the roller in alinement with the shaft. The side walls of the slot 61 are tapered outwardly, as shown at 61^a to permit the convenient insertion of 60 the bracket 62. This is done with the roller

in an inclined position with the other end thereof adjacent the end of the opposite side frame. After the bracket 62 has passed into engagement with the slot 61, the trunnion 30 can be swung into the opposite 70 slot 31 and passed into engagement with the notch 33^b in the latch 33 which can be manually elevated against the spring 36 to permit this operation. In this way both of the rollers are detachably mounted in 75 the frame of the machine and can be readily withdrawn therefrom to permit the insertion of new rollers containing new rolls of the impression sheet 20.

In using the device, one end of the sheet 80 20 which is originally wound on the roller 21 is carried through the slots 16 and 17 over the table 11 and the end thereof is attached to the roller 22. The pawl 53 can then be elevated to permit the free rotation 85 of the ratchet wheel 51 and the lever 48 can be operated to wind a portion of the impression sheet on the roller 22. When the impression sheet is stretched taut upon the table 11, it can be maintained in this condition by means of the pawls 53 and 54. 90 These pawls are directed in opposite directions from their pivots 55 and the teeth of the ratchet wheels 51 and 52 are correspondingly oppositely inclined so that the pawl 53 is adapted to prevent the rotation of the ratchet wheel 51 in a clockwise direction, as viewed in Fig. 2, while the pawl 54 is adapted to prevent rotation of the ratchet wheel 52 in an anti-clockwise direction, as 95 viewed in Fig. 2. In this way the ratchet wheels can both be located to maintain the impression sheet in the desired taut position on the table to form a copy of the written or typewritten matter. In using the 100 apparatus, the impression sheet 20 is first moistened with a sponge or the like and the typewritten sheet or other matter to be copied is then placed face downwardly upon the sheet 20 with the ends thereof projecting 105 between the guide flanges 27, thereby effecting the transfer of the typewritten or other record to the upper surface of the impression sheet. Blank sheets of paper are then laid successively upon the guide block 27 and 110 are pressed upon the impression sheet by rolls, or the like, in order to effect the desired reproductions.

Although I have shown and described a certain embodiment of the invention for 115 purposes of illustration, it will be understood that it may be constructed in various other forms without departing from the scope of the appended claims.

I claim:

1. In combination, a supporting table, side frame members supporting said table, means mounted at the ends of said table for moving and adjusting an impression sheet on said table, and a movable member adapt- 120

ed to rest on said sheet beyond and adjacent the end of said table for guiding said sheet and maintaining the same in contact with said table.

- 5 2. In combination, a supporting table, side frame members supporting said table, means mounted at the ends of said table for moving and adjusting an impression sheet on said table, a movable member adapted to 10 rest on said sheet beyond and adjacent the end of said table, and means associated with said movable member for positioning a sheet of paper on said impression sheet.
3. In a copying machine, a table, supporting means therefor, a roller carried by said means, a shaft adapted to actuate said roller, a member carried by the end of said shaft and having a transverse slot in the end face thereof, and a bracket attached to the end of 20 said roller for engaging said slot.

4. In a copying machine, a table, supporting means therefor, a roller carried by said means, a shaft adapted to actuate said roller, a member carried by the end of said 25 shaft and having a transverse slot in the end face thereof, and a bracket attached to the end of said roller for engaging said slot, said bracket having transverse parts adapted to coat with the end surfaces of said 30 slotted members at the end of said slot.

5. In a copying machine, a table, supporting means therefor, a roller carried by said means, a shaft adapted to actuate said roller, a member secured to the end of said shaft 35 and having transverse grooves in the end face thereof, the lateral walls of said groove being tapered outwardly, and a plate seated in the end of said roller and adapted to engage said groove.

- 40 6. In a copying machine, a table, supporting means therefor, a roller carried by said means, a shaft adapted to actuate said roller, a member secured to the end of said shaft and having transverse grooves in the end 45 face thereof, the lateral walls of said groove being tapered outwardly, and a plate seated in the end of said roller and adapted to engage said groove, the ends of said plate being bent transversely to engage the surfaces 50 of said member at the ends of said slot.

7. In a copying machine, side-frame members, a table supported thereby, a roller adapted to extend between said side frame members on one side of said table, a driving 55 shaft journalled in one of said side frame

members, means for forming a detachable connection between one end of said roller and said shaft, the side frame member opposite said shaft being provided with a slot, and a trunnion secured to the other end of said 60 roller and detachably engaging said slot.

8. In a copying machine, side-frame members, a table supported thereby, a roller adapted to extend between said side frame members on one side of said table, a driving shaft journalled in one of said side frame members, means for forming a detachable connection between one end of said 65 roller and said shaft, the side frame member opposite said shaft being provided with a slot, a trunnion secured to the other end of said 70 roller and detachably engaging said slot, and means for detachably holding said trunnion in alignment with said shaft.

9. In a copying machine, side-frame members, a table supported thereby, a roller adapted to extend between said side frame members on one side of said table, a driving shaft journalled in one of said side frame members, means for forming a detachable 80 connection between one end of said roller and said shaft, the side frame member opposite said shaft being provided with a slot, a trunnion secured to the other end of said 85 roller and detachably engaging said slot, and a pivoted latch member pivoted on said slotted side frame member and adapted to hold said trunnion in alignment with said shaft.

10. In a copying machine, side-frame members, a table supported thereby, a roller adapted to extend between said side frame members on one side of said table, a driving shaft journalled in one of said side frame members, means for forming a detachable connection between one end of said 90 roller and said shaft, the side frame member opposite said shaft being provided with a slot, a trunnion secured to the other end of said 95 roller and detachably engaging said slot, a pivoted latch member pivoted on said slotted side frame member and adapted to hold said trunnion in alignment with said shaft, and means connected to said slotted side frame members for normally holding 100 said latch member in engagement with said trunnion.

In testimony whereof, I have subscribed my name.

GEORGE SABIK.
